US00D898705S

(12) **United States Design Patent** (10) Patent No.: **US D898,705 S**
Wendling et al. (45) Date of Patent: **** Oct. 13, 2020**

(54) **REMOTE CONTROL**

- (71) Applicant: **Crestron Electronics, Inc.**, Rockleigh, NJ (US)
- (72) Inventors: **Byron Wendling**, Nyack, NY (US); **Wayne Owens**, Pearl River, NY (US); **André Poulheim**, Frechen (DE)

- (73) Assignee: **Crestron Electronics, Inc.**, Rockleigh, NJ (US)

(**) Term: **15 Years**

(21) Appl. No.: **29/680,704**

(22) Filed: **Feb. 19, 2019**

Related U.S. Application Data
